FISHING LINE SINKER

Leslie E. Young, deceased, late of Cincinnati, Ohio, by Maureen Young Imfeld, administratrix, Hamilton, Ohio

Filed Oct. 31, 1962, Ser. No. 72,348

Term of patent 14 years

(Cl. D31—4)

FIG. 1 is a top, plan view showing my new design for a fishing line sinker.

FIG. 2 is a bottom, plan view of the fishing line sinker.

FIG. 3 is a side elevation view taken from the left side of the fishing line sinker shown in FIG. 1.

FIG. 4 is a side elevation view taken from the right side of the fishing line sinker shown in FIG. 1.

FIG. 5 is a section taken on line 5—5 of FIG. 1.

FIG. 6 is a section taken on line 6—6 of FIG. 1.

I claim:

The ornamental design for a fishing line sinker, as shown.
